(57) **CLAIM**

The ornamental design for a tape cassette for label printer, as shown and described.

DESCRIPTION

FIG. 1 is a front perspective view of the tape cassette for label printer;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is a detail view of the portion marked "8" in FIG. 1;

FIG. 9 is a front perspective view of the gear isolated from the body of the tape cassette; and,

FIG. 10 is a rear perspective view of the gear isolated from the body of the tape cassette.

The evenly spaced broken lines depict unclaimed parts of the tape cassette for label printer and form no part of the claimed design. The dot-dash chain line forming a rectangular shaped box around a portion of FIG. 1 depicts an area shown as a detail view in FIG. 8, and forms no part of the claimed design.

1 Claim, 10 Drawing Sheets
